M. Ralend

UNITED STATES PATENT OFFICE.

JAKUB SADOWSKI, OF SCRANTON, PENNSYLVANIA.

RAIL SUPPORT.

Application filed April 1, 1922. Serial No. 548,719.

To all whom it may concern:

Be it known that I, JAKUB SADOWSKI, a citizen of the United States, residing at Scranton, in the county of Lackawanna and State of Pennsylvania, have invented certain new and useful Improvements in Rail Supports, of which the following is a specification.

An important object of this invention is 10 the provision of means for securing and preventing railway rails from spreading and also from longitudinal separation.

A further object is the means provided whereby the rails are rigidly interlocked 15 with spacing plates adapted to be secured to the usual type of railway ties or sleepers.

These and other objects of equal importance are attained by the novel construction and arrangement of parts hereinafter described and shown in the accompanying drawings, forming a material part of this disclosure and in which:—

Fig. 1 is a fragmental top plan view of the rail securing device as assembled.

25 Fig. 2 is a side view of the same.

Fig. 3 is a fragmental perspective view of one end of the rail spacing plate.

Fig. 4 is a fragmental perspective of the rail end, showing the interlocking elements.

30 Figure 5 is a side view of the type of bolt used in the construction.

Referring to the drawing in detail, the numeral 6 represents the head of a rail having a vertical web 7 positioned centrally of the double flanged bottom 8.

An arcuate ended spacing plate 10 is provided with transverse parallel sided depressions 11, near the ends. Oppositely opposed notched teeth 12 are formed with the 40 depressions and are of equal width.

The spaces 13 are of similar width, while the center spaces 14 are approximately twice the width of the teeth 12.

Clamps 15 are provided with a bevelled 45 under side 16 adapted to impinge against the rail flanges 8; clamp screws 17 pass freely through the clamps and are threadably engaged in the threaded openings 17', serving to bind the clamps, rails and plates 50 rigidly together.

Integral bosses 18, formed on the under side of the clamp members 15 prevent by engagement within rectangular recesses 19 in the plate 10, any outward or retractive 55 movement of the clamp elements.

Referring to Fig. 4, it will be seen that

notches 20 are punched through the opposite flanges at the ends of the rails; these notches are adapted to interlock with the toothed elements 12 of the recessed plate 10, 60 the tooth 21 at the end of the rail being one half the width of the slot 14, permitting two rails to abut and be rigidly secured centrally of the plate 10.

From the foregoing, it will be seen that 65 a practical means has been disclosed by which rails may be positively and removably connected to transverse plates having interlocking means therewith and adapted to completely overcome the danger of rails 70 spreading and compelling the rails to be maintained in intimate end engagement, sufficient looseness being provided to permit the necessary expansion and contraction 75 in the rail lengths.

Having thus described my invention, what I claim and desire to secure by Letters Patent, is:—

1. In a non-spread rail support, the combination with a flanged rail having spaced 80 slots through the flanges at the ends thereof, of a rail spacing plate having transverse depressions formed on the top of said plate, rectangular teeth oppositely disposed and extending toward the center of the depression, a plurality of recesses formed between said teeth, one of the opposite pair of recesses being of greater width than the other recesses, and means with said teeth and recesses for interlocking the rails and spacing 85 plates.

2. In a non-spread rail support, the combination with a flanged rail, having spaced slots through its flanges, of a plate for spacing the rails, there being depressions, 90 transversely of the plate receptive of the slotted ends of said flanged rails, clamps for holding the rails in said depressions, screws for securing the clamps, and means for preventing said clamps from retractive movement.

3. In a non-spread rail support, the combination with a flanged rail, of a rail spacing plate securable to said rails and having recesses formed at the ends, there being slots 105 formed at the ends of the rail flanges, toothed prongs adjacent the slots, the outer prong being one half the width of the next adjacent prong, interlocking projections in the recess of the plate, and means therewith 110 for engaging the abutting end of a pair of rails.

4. In a non-spread rail support, the combination with a flanged rail, of a rail spacing plate, toothed interlocking means between said plate and rails, clamps for maintaining intimate connection between the plates and the rails, screws for securing the clamps, projections on said clamps, co-act-

ing depressions formed in the plates, means for preventing retractive action of the clamps, and means with said spacing plate 10 for maintaining said rails in parallel alignment.

In witness whereof I affix my signature.

JAKUB SADOWSKI.
